UNITED STATES PATENT OFFICE.

GEORGE B. IRELAND, OF ROCHESTER, NEW YORK, ASSIGNOR TO TAYLOR INSTRUMENT COMPANIES, OF ROCHESTER, NEW YORK, A CORPORATION OF NEW YORK.

COMBINED PRESSURE-INDICATING AND VALVE-OPERATING MECHANISM.

Application filed October 7, 1920. Serial No. 415,299.

To all whom it may concern:

Be it known that I, GEORGE B. IRELAND, of Rochester, in the county of Monroe and State of New York, have invented certain new and useful Improvements in Combined Pressure-Indicating and Valve-Operating Mechanism; and I do hereby declare the following to be a full, clear, and exact description of the same, reference being had 5 to the accompanying drawings, forming a part of this specification, and to the reference numerals marked thereon.

This invention has to do with pressure indicating and valve operating mechanism 10 of a character adapted for use in conjunction with industrial processes such as those involving the employment and control of fluid pressures, fluid heating or cooling mediums, and the like, the chief object of 15 the invention being to provide an improved mechanism adapted for indicating a range of pressure and for automatically operating a valve or valves to be controlled in accordance therewith, at any predetermined point in said range. To these and other ends the invention consists in certain improvements and combinations of parts, all as will be hereinafter more fully described, the novel features being pointed out in the claims at the end of the specification.

In the drawings:

Figure 1 is a front exterior elevation of a mechanism embodying the present invention.

25 Figure 2 is a similar view enlarged, with the casing removed.

Figure 3 is a side elevation of the same as viewed from the left in Figure 2.

Figure 4 is a detailed view partly in section as seen from the line 4^a—4^a in Figure 3, and

Figure 5 is an enlarged section on the line 5^a—5^a of Figure 3.

Similar reference characters throughout 45 the several views indicate the same parts.

The embodiment of the invention selected for disclosure at the present time is intended merely by way of illustrating of the principles involved and the preferred mode of 50 application thereof, and is susceptible of various modifications of the details of construction and operation. The present embodiment is particularly adapted for use in conjunction with vulcanizing apparatus of 55 a character employed for subjecting articles or material to hydraulic pressure in a heated

chamber. In such apparatus it is desirable to apply the required degree of pressure before the steam or other heating medium is admitted to the chamber, and the present invention provides mechanism, responsive to the hydraulic pressure employed, for controlling the steam valve to admit the steam when the desired degree of pressure has been obtained. As the operating pressure desired may be different under different conditions, means is provided for adjusting the valve controlling parts to operate at predetermined pressures, together with means for conveniently indicating the 70 selected setting of such adjusting means.

Referring to the drawings and more particularly to Figures 1 and 2 thereof, there is shown a base plate 10 on which is secured a substantially cylindrical casing 11 enclosing the operating parts shown in Figure 2, over which may be placed a dial 12 enclosed by the usual glass or crystal. The base plate carries an annular flange 13, Figure 2, on which is formed, at the right, a bracket 14 supporting a pipe joint or union 15, to the outer end of which is connected a pipe 16 leading to a suitable source of fluid pressure such, for example, as compressed air. To the other end of the union within the casing is connected a pipe 17 leading to a substantially cylindrical secondary valve housing 18, and communicating with a laterally extending passageway 19 therein. In the opposite side of the housing is formed a 75 similar passageway 20, and both of these passageways communicate at their inner ends with an irregular longitudinal passageway 21, in which is formed as at 22 a seat for a ball valve 23, carried on a stem 24, extending upwardly through and above the end of the housing. The adjacent portion of the longitudinal passageway 21 fits the stem closely enough to guide the latter and the ball valve while, however, permitting the slow escape therethrough around the stem of any pressure in the passageway 20. The opposite side of the ball valve is also provided with a stem 25 extending within a bore 26 in a plug 27 threadedly engaging in an opening 28 within the lower end of the valve housing, and a spring 29 coiled about stem 25, and bearing at its lower end against the plug and at its upper end against the valve, serves to urge the latter against its seat to shut off communication from 80 passageway 19 to passageway 20. The latter has 85

- communicating therewith a pipe 30 connected to a union 31 supported in a bracket 32 on the flange 13 of the base plate, and the outer end of the union communicates with a pipe 33 leading to the main valve to be controlled. The latter is preferably of the well known diaphragm type opened by pressure transmitted through the pipe 33 and closed by a spring.
- 10 The means for operating the secondary ball valve 23 downwardly, against the pressure of its spring, to transmit pressure to the main valve, comprises, preferably, a rod 33^a connected with the upper end of the 75
15 valve stem and having pivotally connected with its upper end, as at 34, one arm of a lever 35 pivotally secured as by means of a screw 36 on a post 37. The latter is carried by a plate 38 formed with a pair of 80
20 elongated slots 39 each embracing a pair of screws 40 in the base plate, so that plate 38 is secured and guided for vertical movement on a bearing surface 41 on the base plate. Threadedly engaging an opening in post 37 is a spindle 42 having a smooth 85
25 upper end or shank 43 slidably supported in a bracket 44 on the base plate. Downward movement of the spindle in its bracket is limited by a collar 45 on the spindle and a 90
30 spring 46, coiled above the latter and bearing at its ends against post 37 and bracket 44, serves to maintain collar 45 of the spindle in engagement with bracket 44 but permits a yielding upward movement of the 95
35 spindle and the post 37 with which it is connected in case of excessive upward actuation of the lever 35. A squared upper end 47 of the spindle, accessible through an 100
40 opening in the casing wall 11, provides for its rotation to adjust the position of plate 38 and post 37 which pivotally supports the lever. The other and longer arm of the 105
45 lever bears on the upper side of a post or projection 48 preferably fixed adjacent the outer end of a pressure responsive element or Bourdon spring 49, the inner end of which is supported by attachment to a post 50 on a bracket 51 on the base plate.
- 46 Communicating with the inner end of 110
50 the Bourdon spring is a pipe or tube 52 extending downwardly adjacent the bottom of the base plate and connected with a union 53 supported in a bracket 54 on the plate. In the use of the mechanism the outer end 115
55 of union 53 is connected with the hydraulic or other fluid pressure system of the press commonly employed for applying pressure to the material or articles treated in a vulcanizing container. Such fluid actuated 120
60 compressing means usually operates with a comparatively high degree of pressure which would be destructive to many forms of pressure responsive elements such, for example, as most capsular diaphragms. This difficulty has been solved by the employment of 125
65

a heavy Bourdon spring such as described above and shown in the drawings, which readily withstands the highest pressures encountered and is capable of exerting sufficient force under pressure to easily operate pressure indicating and valve controlling mechanism.

It is apparent from the above described construction that the application of pressure to the Bourdon spring serves to expand or 75
70 unwind the latter so as to raise the longer end of lever 35 and depress its opposite or shorter end, which, by means of rod 33^a, positively opens the secondary valve. The 80
85 action of the lever on the valve in response to the movement of the Bourdon spring may be regulated and controlled by adjustment of spindle 42 to raise or lower the pivotal support of the lever. Thus the mechanism 90
95 may be set to open the valve at any predetermined extent of expansion of the spring, corresponding to any predetermined point in the range of actuation of the latter. Referring to Figure 5 it is apparent that the secondary valve is moved toward its seat by its spring 29 and by the force of the fluid pressure in passageway 19 working together, and that the valve is moved in the opposite direction against both of these forces by the rod 33^a, so that the secondary valve is moved in both directions by forces of a positive character. The eccentric support of lever 35, with its longer arm co-operating with the spring, tends to reduce any inaccuracy which may be present in the 100
105 action of the latter, and facilitates accurate control of the secondary and main valves.

The means for indicating the degree of actuation of the pressure responsive element, or Bourdon spring, comprises, preferably, a 110
115 link 55 of adjustable length pivotally connected with the projection 48 of the spring and also with a link 57 adjustably secured to a gear sector 58 pivotally supported at 120
125 59 on a frame 60 which in turn is pivotally supported on a spindle 61 rotatably carried by the base plate. Frame 60 has a depending arm 62 provided with a slot 63 through which loosely passes the reduced end 64 of a spindle 65 rotating and sliding freely in a post 66 on the base plate. The reduced end 64 of the spindle threadedly engages an opening in post 67 on the base plate, and the spindle is provided with a collar 68 against which arm 62 is maintained by a collar 69 sliding on the reduced portion of the spindle and urged toward the arm by a spring 70 coiled about the spindle and bearing at its respective ends against collar 69 and post 67. Spindle 65 has a squared outer end 71, accessible through an opening in the casing wall 11, for rotating the spindle and thereby pivotally moving frame 60 for adjusting pivot 59 of the gear sector. The latter has its teeth 72 meshing with a pinion 130

73 fixed on spindle 61, and the latter projects through dial 12 and has fixed thereon a pointer 74, the end of which is movable over suitable indicia 75 on the dial. The latter in the present instance represents a range of pressures up to 2,000 pounds, and, by means of the various adjustments described above, the operation of the pointer may be adjusted to indicate accurately the fluid pressures applied at any instant to the vulcanizer press.

10 A means is provided for conveniently indicating the position of adjustment or setting of the pivotal support of lever 35, which determines the degree of pressure in the vulcanizer at which the secondary valve is opened, comprising, preferably, a rack bar 76, Figure 4, fixed on the lower end of plate 38 and having teeth meshing with a pinion 77 fixed on a spindle 78 rotatably carried in a frame 79 on the base plate. Spindle 78 extends through the main dial 12 and has fixed thereon a pointer 79^a movable over a small dial 80 having pressures marked thereon up to 2,000 pounds corresponding to the markings of the main dial. The adjustment of the pivotal support of lever 35 by means of spindle 47 thus correspondingly sets the pointer 79^a through the connections described to indicate the vulcanizer pressure corresponding to which the secondary valve is opened.

15 The invention thus embodies a simple and effective mechanism for indicating at all times the pressure existing in the vulcanizer press and for automatically turning on the steam or other heating medium when a predetermined pressure in the vulcanizer has been reached, thereby preventing premature application of heat in the vulcanizing chamber and consequent injury to the material or article under treatment. The parts are compactly arranged, positive and reliable in action, and readily adjustable as occasion 20 may require, while the dial as appears in Figure 1 conveniently shows at a glance the condition of the apparatus, including the pressure applied in the vulcanizer as well as the degree of pressure at which the secondary valve is set to open.

25 I claim as my invention:

1. A combined indicating and regulating mechanism comprising a fluid pressure line, a valve controlling said line, a pressure actuated element, a dial and pointer for indicating the degree of actuation of said element, and connections between said element and valve including an adjustably mounted lever for operating said valve.

30 2. A combined indicating and regulating mechanism comprising a fluid pressure line, a valve controlling said line, an element adapted for connection with a source of pressure and to be moved thereby, means for indicating the degree of movement of said ele-

35 ment, a lever cooperating with said element and with said valve for operating the latter, and an adjustable pivotal support for said lever to vary the action thereof.

3. A combined indicating and regulating mechanism comprising a fluid pressure line, 40 a valve controlling said line, an element adapted for connection with a source of pressure and to be moved thereby, means for indicating the degree of movement of said element, a lever cooperating with said element and with said valve for operating the latter, an adjustable pivotal support for said lever to vary the action thereof, and a dial and pointer for indicating the position of adjustment of said pivotal support.

4. A combined indicating and regulating mechanism comprising a fluid pressure line, a valve controlling said line, a Bourdon spring adapted for connection with a source of relatively high pressure for actuation by the latter, means for indicating the degree of actuation of said spring, and adjustable connections between said spring and valve for operating the latter at a predetermined point in the range of actuation of said spring.

5. A combined pressure indicating and regulating mechanism comprising a fluid pressure line, a valve controlling said line, a Bourdon spring adapted for connection with a source of relatively high pressure for actuation by the latter, a dial and pointer for indicating the degree of actuation of said spring, a lever connected with said spring and with said valve for operating the latter, and adjusting means for varying the movement of said lever to operate said valve at a predetermined point in the range of actuation of said spring.

6. A combined pressure indicating and regulating mechanism comprising a fluid pressure line, a valve controlling said line, a Bourdon spring adapted for connection with a source of relatively high pressure for actuation by the latter, a dial and pointer for indicating the degree of actuation of said spring, a device for adjusting the action of said dial and pointer, a pivotally supported lever connected with said spring and with said valve to operate the latter, and adjusting means for said lever support for varying the movement of said lever and operating said valve at a predetermined point in the range of movement of said spring.

7. A combined indicating and regulating mechanism comprising a casing, a fluid pressure line extending through said casing, a valve in said casing controlling said line, a pressure responsive element, an indicator for indicating the degree of actuation of said element, actuating connections between said element and valve including a lever, an adjustable pivotal support for said lever,

a spindle rotatably carried by the casing and having threaded connection with said support for adjusting the latter, and means for indicating the adjustment of said support.

- 5 8. In a combined indicating and regulating mechanism, a fluid pressure line, a valve controlling said line, a pressure responsive element, an indicator for indicating the degree of actuation of said element, a lever connected with said element and with said valve for actuating the latter, a movably supported plate having a pivotal support for said lever, means for adjustably moving said plate, a dial and pointer, and a connection between said plate and pointer for indicating the adjustment of said plate.
- 10
- 15

9. In a combined indicating and regulating mechanism, a casing, a fluid pressure line, a valve controlling said line, a Bourdon spring in said casing, an indicator connected with said spring for indicating the movement thereof, a lever connected with said spring and valve for actuating the latter, a plate slidably mounted on the casing and pivotally supporting said lever, a threaded spindle carried by said casing and connected with said plate for adjustably sliding the latter, and means for indicating the adjustment of said plate, comprising a dial and pointer and a rack and pinion connection between said plate and pointer. 20 25 30

GEORGE B. IRELAND.
